UNITED STATES PATENT OFFICE.

WILLIAM PARKER HAMMOND, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

CUT-SOLE RACK.

1,348,173.

Specification of Letters Patent. Patented Aug. 3, 1920.

Application filed January 30, 1915. Serial No. 5,243.

To all whom it may concern:

Be it known that I, WILLIAM P. HAMMOND, a citizen of the United States, residing at Boston, in the county of Suffolk and 5 State of Massachusetts, have invented certain Improvements in Cut-Sole Racks, of which the following description, in connection with the accompanying drawings, is a specification, like reference characters on 10 the drawings indicating like parts in the several figures.

This invention relates to racks and is herein shown embodied in a cutsole rack such as is used in shoe factories to store and 15 transport quantities of cutsoles.

It is found that the problem of storage of non-used racks becomes a serious matter in shoe factories. The number of racks in use varies greatly from time to time and 20 as the racks are bulky many factories fail to have on hand the full number they need during the periods when business is heavy because of the room taken up by them when not in use. It is obvious also that the cost 25 of such bulky articles is increased by freight charges. A demand has therefore arisen in the trade for racks which can readily be knocked down and packed away in small compass when not in use.

It is of great importance also that nails 30 and screws be dispensed with in the joints of shoe factory racks as these fastenings waste a great deal of time in the knocking down of the racks, and, furthermore, are liable to be carelessly inserted, leaving projecting portions which injure the articles 35 piled on them.

Two phases of this problem are treated in my Patents No. 1,099,849, June 9, 1914, 40 for a rack, and No. 1,100,072, June 16, 1914, for a shoe rack.

It is the object of my present invention to provide a rack in which defects of racks heretofore used shall be obviated. The 45 rack herein shown and described is so constructed that it may be readily knocked down without the use of special tools and without the loss of much time, that all the fastenings which have to be loosened in the 50 knocking down operation are a small num-

ber of bolts, and that shelves and partitions are locked in place by a relatively small number of bolts.

In the accompanying drawings,

Figure 1 is a front elevation of the rack, 55 and

Fig. 2 is a broken away detail perspective of one end thereof, showing a top, a bottom, and one intermediate shelf.

The rack shown consists of a steel frame 60 carrying wooden shelves and partitions. The steel frame is substantially like that shown in my Patent No. 1,100,072. It has a base frame comprising the parallel angle bars 1, joined by the riveted straps 2, and carrying the casters 3. A similar end frame comprising the angle bars 4 and the riveted straps 5 is mounted on each end of the base frame by means of a bolt and nut 6 at each corner of the base frame. The upper ends of the angle bars 4 in each end frame are joined by a tube 7 as in my Patent No. 1,108,363, Aug. 25, 1914, for a joint. The braces 8 hold the end frames in vertical position. The steel frame so far described may be folded upon removal of the 70 four bolts 6, as shown in my Patent No. 1,100,072.

The skeleton of a rectangular frame is formed by riveting together four angle bars 80 9 through the overlapping ends of their horizontal flanges. The rivet at each corner also fastens to this rectangular frame a little angle 10 the vertical flange of which is bolted to an upright 4 by the bolt 11. 85 The steel skeleton is thus made rigid. A second similar rectangular frame, comprising the four angles 12, is fastened between the ends of the uprights 4. In the drawing, it is shown as fastened by bolts 13 90 extending through the vertical flanges of the end angles 12 and the angles 4. A third frame, similarly comprising angles 14, rests loosely on the little angles 14' which are riveted to the upright angles 4. Straps 12' 95 (see Fig. 1) reinforce the frames comprising the angle bars 9, 12 and 14. It is obvious that the different means of fastening the rectangular frames to the end frames may be interchanged or varied. There may, 100

of course, be any desired number of intermediate frames similar to that comprising the angle bars 12. The intermediate and lower frames are shown sloping downward 5 and backward to facilitate the insertion, retaining and removal of the soles, but it is obvious that they may be placed in any desirable position.

Each of the frames comprising the bars 10 9, 12, 14 also comprises a series of wooden shelves, fillers or horizontal partition members 15 which may be of any desired width and which rest upon the horizontal flanges of the frame bars, thus forming trays. The 15 members 15 are preferably arranged substantially directly above one another, so that they and the apertures in and between them register. These apertures form what are in effect a series of registering slots in 20 the frames comprising the bars 9, 12, 14, in which the vertical partition members 19 and 22, to be described, are supported. Each of the members 15 is slotted at each end in its own plane as at 16. Bars 17 of 25 substantially the length of the rack are placed in the slots at the corresponding ends of a series of alining shelves and are bolted to the horizontal flanges of the frame bars 9, 12, 14, respectively at suitable intervals 30 by the bolts 18. This construction holds the shelves firmly in place and at the same time renders them readily removable. The bolts 18 do not project above the upper faces of the shelves 15, and furthermore are in the 35 planes of the slats 22, so that they will not be touched by the articles placed on the rack.

Dowel rods 19, passing through holes 20 in the intermediate shelves and seated in 40 sockets 21 in the top and bottom horizontal partition members form a rear wall or vertical partition member for the rack. The side walls of the rack compartments are formed by vertical partition 45 members which may be formed as wooden slats 22, mounted between adjacent horizontal partition members 15, and slotted transversely across their ends, as at 23. Slots 24 are cut across the bottoms of the 50 upper and lower shelves 15, and threaded tie bolts 25 extend through the end angle bars 9, 14, the slots 23, 24, and are held in place by nuts 26.

In order to take down the rack for shipment or storage the bolts 11 are removed, whereupon the upper frame 9 with its members 15 and tie bolts 25 may be readily removed. The dowel rods 19 and the slats 22 and the bottom frame 14 may be readily 60 lifted out, and the tray 12 is released by removing the bolts 13. The steel bottom and ends are then folded as shown in my Patent No. 1,100,072, above referred to. It will be seen that it is unnecessary to remove the 65 shelves 15 from their supports in taking

down the rack, but that they can readily be removed if damaged, or if necessary for any other reason, by removing at most two rows of bolts 18. A broken slat 22 can be replaced by the removal of only one bolt 25, 70 and a broken dowel rod by the removal of one row of bolts 18. The whole rack, as shown, can be knocked down for storage or packing by the removal of the twelve bolts 6, 10, 13, and if the frame 12 be supported 75 like the frame 14, there will be only eight bolts to remove.

Having described my invention, what I claim as new and desire to secure by United States Letters Patent is:—

1. A rack comprising a plurality of horizontally extending frames, each having a series of fillers in its plane, said fillers registering across the series of frames, and partition members, each extending transversely 85 across the planes in which said frames and fillers lie, said members lying between the fillers and forming pockets for the reception of articles carried by the rack.

2. A rack comprising a frame having a 90 slot, a partition member having a slot and lying in the plane of said first-named slot, and a lock rod in said frame engaging said second-named slot.

3. A rack comprising two opposed frames 95 having registering slots, a partition member having slots in its ends and mounted in said registering slots, and lock rods engaging said slots and mounted in said frames.

4. A rack comprising a plurality of 100 frames having registering slots, a series of other members positioned in said slots having registering slots, and lock rods positioned in said latter slots.

5. A tray for a rack comprising a supporting frame, a series of slotted fillers for said frame, a common lock rod in said slots and a bolt between two of said fillers for fastening said lock rod to said frame, said bolt being constructed and arranged to lie 110 entirely below the upper surface of said filler.

6. A tray for a rack comprising a supporting frame, a slotted filler, a lock rod, and a fastening member connecting said 115 frame and rod substantially in line with said slot and lying without said filler.

7. A tray for a rack comprising a supporting frame, a series of slotted fillers therefor, and a lock rod for said fillers bolted 120 to said frame between said fillers.

8. A tray for a rack comprising a supporting frame having an angle iron member with a horizontal flange, a filler having a slot across its end lying in contact with 125 said horizontal flange, and a lock rod in said slot bolted to said horizontal flange outside of said filler.

9. A tray for a rack comprising a supporting frame having two opposed angle 130

iron members with horizontal flanges and their angles opposed, a filler having slots across its ends, lying in said angles, in contact with said horizontal flanges, and lock 5 rods in said slots bolted to said horizontal flanges outside of said filler.

In testimony whereof I have signed my

name to this specification in the presence of two subscribing witnesses.

WILLIAM PARKER HAMMOND.
